UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

HEATING APPARATUS

Original application filed April 25, 1923, Serial No. 634,492. Divided and this application filed December 26, 1930. Serial No. 504,718.

My invention belongs to that general class of devices known as heating apparatus, and relates more particularly to an improved radiator construction, or the like, for steam, 5 hot water or other similar systems and is a division of my copending application, Serial No. 634,492, filed April 25, 1923 and allowed December 3, 1930, which has now matured into Patent No. 1,810,721, granted June 16, 1931.

10 The invention has among its objects the production of an apparatus of the kind described that is simple, compact, attractive, inexpensive, of light weight, economical and efficient.

15 One of the principal objects of the invention is to provide a construction in which air flowing into the structure is positively caused to circulate through the device.

Another object of the invention is to provide a radiator having means for causing air 20 to flow in the above mentioned manner.

Another object of the invention is to provide a stack having an opening at its upper portion and an opening at the lower portion 25 thereof and having a radiator arranged at the lower opening, the radiator providing means for directing air in an upwardly direction relatively to the stack.

It is another object of the invention to 30 provide a stack having a radiator disposed at the lower opening thereof in a manner to cause air entering the stack to be heated and be directed in an upwardly and rearwardly direction relatively to the interior of the stack.

Another object of the invention is to 35 provide a construction such as that just referred to having means for controlling the passage of air through the stack and also to provide a stack having perforated shelves to thus 40 provide a warming closet for various elements or commodities which it is desired to heat.

The invention has these and other objects, 45 all of which will be described in detail and more readily understood when read in conjunction with the accompanying drawings forming a part hereof which illustrate various embodiments of which the invention is 50 susceptible, it being therefore obvious that

other changes and modifications may be resorted to without departing from the spirit of the appended claims forming a part hereof.

In the drawings, Fig. 1 is a front elevation 55 of a stack embodying the features of invention;

Fig. 2 is a section taken on the line 2—2 of Fig. 1;

Fig. 3 is a section taken on the line 3—3 60 of Fig. 1;

Fig. 4 is a front elevation of a modified construction;

Fig. 5 is a section taken on line 5—5 of Fig. 4; and 65

Fig. 6 is a section taken on line 6—6 of Fig. 4.

The structure shown in Fig. 1 contemplates the utilization of a stack generally designated 10 which is comprised of a front wall 11 and 70 end walls 12 and 13, the rear wall of the stack being provided by a wall such as 14 which, in the present instance, forms a wall of the building structure in which the device is located. 75

The stack generally designated 10 has an opening 15 at the upper portion thereof and an opening 16 located adjacent the lower end thereof. A radiator unit generally designated 17 is located adjacent the lower opening and perforated shelves 18—18 are disposed within the interior of the stack above the radiator generally designated 17. A damper 19 is located within the interior of the stack to regulate the flow of heated air from the stack which also provides a means for regulating the flow of air into the stack. The stack illustrated in Fig. 1 has an opening 20 whereby access to the shelves 18 may be had. This opening 20 is closed by the doors 21 and 22. 80

The radiator generally designated 17 includes headers 23 and 24, tubes 25 and heat radiating fins 26, it being understood that the tubes are arranged in spaced relation to each other as clearly shown in Fig. 1 and that the heat radiating fins extend between the tubes and provide passages whereby air entering the opening 16 in the lowermost portion of the stack may flow into the interior 95

of the stack and be directed in an upwardly and rearwardly direction relatively to the interior of said stack. In the structure shown in Figs. 1 and 2, the radiator unit 17 is disposed diagonally within the interior 5 of the stack and has one end thereof located adjacent the upper extremity of the opening 16 and extends therefrom toward the rear portion of the stack or wall 14 which thus arranges the passages of the radiator at an 10 incline in a manner to direct the incoming air in an upwardly and rearwardly direction relatively to the interior of the stack. A perforated shelf 27 may be arranged at the upper opening 15 of the stack.

It is manifest that the structure just described provides a means whereby air may enter the interior of the stack, be heated and directed in a heated condition upwardly and rearwardly of the stack.

In the construction shown in Figs. 4 to 6, inclusive, a stack 28 is employed which has an opening 29 provided at the upper end thereof and an opening 30 located in the lower-most portion thereof. A radiator or heat exchange unit 31 is arranged in a vertical position across the opening 30. The radiator includes headers 32 and 33 and vertically extending tubes 34 and heat radiating fins 35, the latter of which are arranged at an obtuse angle to the tubes and thus provide passageways which will direct the air flowing through the radiator in an upwardly and also rearwardly direction. A damper 36 is provided to regulate the introduction and escape of air to and from the stack and a deflector 37 is located at the upper opening so as to deflect air laterally of the stack.

By the arrangement just described, it is evident that the passages formed by the fins which are located between the tubes such as 34 provide means for directing the air in an upwardly and rearwardly direction.

From the foregoing description, it is manifest that a simple and efficient construction is provided whereby air to be heated may pass through the radiator or heat exchange unit, be heated thereby and directed into the stack in an upwardly direction relatively to the interior of the stack.

Having thus described the invention, what I claim and desire to cover by Letters Patent is:

1. In a device of the kind described, an enclosure comprising a stack having an opening in the upper portion and an opening in the front wall adjacent the lower portion of the stack, a radiator located at and extending across the lower opening, said radiator having tubes and fins formed of strips providing passageways and providing means for directing air passing therethrough in a lateral and upwardly direction with respect to the interior of the casing and providing means for

circulating air by connection through said stack.

2. In a device of the kind described, an enclosure comprising a vertical stack having front and rear walls, said stack having an opening in the upper portion and an opening in the lower portion thereof, a radiator disposed in the lower opening and having tubes and fins formed of strips providing upwardly and rearwardly extending passageways through which air can pass into said stack, said radiator providing means for heating air and causing circulation thereof through said casing by means of connection.

3. In a device of the kind described, an enclosure comprising a vertical stack having an opening in the upper portion and an opening in the lower portion thereof and a vertically arranged radiator disposed at and extending across said lower opening, said radiator having tubes and fins formed of strips providing upwardly and rearwardly extending passageways through which air can pass into said stack and be directed toward the upper opening to thereby cooperate with said openings in said stack to circulate air through said stack.

4. In a device of the kind described, an enclosure comprising a stack having an opening in the upper portion and an opening in the lower portion thereof, a radiator located adjacent the lower opening and extending from the front to the rear of the stack, said radiator having passageways providing means for directing air passing therethrough in an upwardly and rearwardly direction with respect to the interior of the stack.

5. In a device of the kind described, an enclosure comprising a stack having an opening in the upper portion and an opening in the lower portion thereof, a vertically arranged radiator located at the lower opening, said radiator having passageways providing means for directing air passing therethrough in an upwardly direction with respect to the interior of the stack, said radiator and stack with the openings therein providing means for circulating air by connection through said stack, and means for controlling the passage of air through said stack.

6. In a device of the class described, an enclosure comprising a vertical stack having front and rear walls, said stack having an opening in the upper portion thereof and said front wall having an opening in the lower portion thereof, a radiator vertically disposed in the lower portion of said stack and having vertically arranged tubular fluid passages and upwardly and rearwardly extending passageways, said passageways providing the only means by which air entering said opening can pass through said stack and cooperating with said radiator, stack and openings in the stack to cause circulation of air by

connection through said openings, radiator and stack.

7. In a device of the kind described, an enclosure comprising a stack having an opening in the upper portion and an opening in the lower portion thereof, a radiator located at the lower opening, said radiator having tubes and fins formed of strips providing passageways and said tubes and fins providing means for heating and circulating air by convection and directing air through said passageways in a lateral and upwardly direction with respect to the interior of said casing.

13 In witness whereof, I hereunto subscribe my name this 22nd day of December A. D., 1930.
